UNITED STATES PATENT OFFICE.

WILHELM SCHMITZ, OF HAMBURG, GERMANY.

REGULATING GAS-BURNER.

No. 866,687.

Specification of Letters Patent.

Patented Sept. 24, 1907.

Application filed February 5, 1907. Serial No. 355,796.

To all whom it may concern:

Be it known that I, WILHELM SCHMITZ, a subject of the German Emperor, and resident of No. 33-34 Valentinskamp, Hamburg, Germany, have invented certain new and useful Improvements in Regulating Gas-Burners, of which the following is a specification.

The present invention deals with a device for the regulation of gas-burners.

The opening through which the gas enters is regulated by a needle-valve, and the invention consisting therein is that the latter is triangular in shape, cross-section-wise.

The accompanying drawing represents a form of construction of the invention.

Figure 1, a side view of the device. Fig. 2, a longitudinal section. Fig. 3, a view of the needle-valve, on an enlarged scale. Fig. 4, the valve in connection with a gas-burner.

The device consists of two parts *a* and *b* which are screwed one into the other. The ingoing part *a* has a bottom *c* in which four or more holes are bored, and in the middle and the lower side of the same a conical pointed and triangular shaped pin *e* is fastened. The

part *b* is also provided with a bottom *f*, in the middle of which is a bore-hole opening *g* which will be narrowed 25 and widened by the triangular pin *e* according to the said pin being moved up and down by turning of the part *a*. As soon as the device is adjusted, the parts *a* and *b* can be fixed by the binding screw *i*, which prevents the inner part *a* from unscrewing itself from part 30 *b*, and the arm *h* attached to part *b* holds the part *a* from releasing itself from the lower one.

According to this invention the regulating opening *g* can never be closed completely.

I claim:

In a regulating gas burner, the combination of a base part having an internal threaded chamber and carrying at one end a triangular needle valve around the base of which are gas passages opening from said chamber, a second part screwing upon said base part and having an opening into 40 which the needle valve projects, a set screw for holding said part in adjusted position, and a separate device for preventing the separation of the two parts above mentioned, substantially as described.

WILHELM SCHMITZ.
